VISUAL COMPOSING AND OPTICAL RECORDING MACHINE

Samuel Sachs, 6701 N. 29th St., Arlington County, Va., and Frederick Kastel, St. Michaels, Talbot County, Md.
Filed Feb. 7, 1958, Ser. No. 713,948
12 Claims. (Cl. 95—4.5)

The present invention relates to a machine for visually composing type or other characters into a word, message, or other symbol, and recording such word, message, or symbol, after it is composed by optical means, such as photographic recording.

A salient feature of the present invention resides in its provision for visually observing the selection of a plurality of characters comprising a desired message or symbol, and simultaneously composing and observing the composition of all said characters with respect to one another, so that the entire composition of the symbol and relative orientation and relation of the selected characters may be fully adjusted and justified visually. After the entire symbol has been composed to the satisfaction of the operator, the machine may then be utilized to record said symbol as thus composed optically, as by photographic means.

To this end, the machine utilizes a plurality of alphabetical and numerical fonts, or other basic character designation means, the number of fonts depending upon the number of characters it is desired to simultaneously compose into a symbol. These fonts are used to project or otherwise optically transpose the selected characters simultaneously onto a screen. The image thus created on the screen is made visible to the operator, and by observation of this image he may adjust the fonts and/or the optical system transposing the font characters, to adjust, compose, and justify all the characters individually until he has obtained the image of the symbol in the form and composition desired. Once satisfied with the composition of the symbol, the operator may then optically apply the image as observed to a recording medium, such as a photographic plate, or the like.

Accordingly, it is one object of the present invention to provide a visual composing and recording machine which enables a symbol comprising a plurality of characters to be completely composed under the observation of the operator, and which provides for the recording of such symbol as thus composed.

Another object of the present invention is to provide a visual composing and optical system recording machine which enables a symbol comprising a plurality of characters to be completely composed under the observation of the operator, and which provides for the optical recording of such symbol as thus composed.

Another object of the present invention is to provide such a machine, wherein the plurality of characters comprising the symbol are optically transposed onto a screen, from which the composition of all the characters and the adjustment thereof may be had simultaneously under the observation of the operator.

Other objects and advantages of the present invention will become apparent to those skilled in the art from a consideration of the following detailed description of one exemplary embodiment of the present invention, had in conjunction with the accompanying drawings, in which like numerals refer to like or corresponding parts, and wherein:

FIG. 1 is a vertical sectional view of a machine embodying the present invention;

FIG. 2 is a longitudinal sectional view of the machine illustrated in FIG. 1, taken along the line 2—2 of FIG. 1;

FIG. 3 is an enlarged detailed top plan view of a por-

2

tion of a font and font carrier assembly used in the machine of FIG. 1;

FIG. 4 is a vertical sectional view of the font and font carrier assembly shown in FIG. 3, taken along the line 4—4 of FIG. 3;

FIG. 5 is a cross-sectional view of the font and font carrier assembly of FIG. 3, taken along the line 5—5 of FIG. 4;

FIG. 6 is an enlarged detailed top plan view of a portion of the machine of FIG. 1, showing the film carrier and adjusting structure therefor; and

FIG. 7 is a further enlarged detailed view of a portion of said film carrier and adjusting assembly.

Referring particularly to FIGS. 1 and 2, the present machine comprises a housing 10 having a bottom wall 11, top wall 12, side walls 13, end wall 14, and front panel 15. A panel 16 is provided adjacent the bottom edge of the front panel 15 spaced upwardly from the bottom wall 11, defining an aperture 18 between panel 16 and bottom wall 11, for purposes to be subsequently described. The housing thus described may be mounted on any suitable support, such as legs 17.

Within housing 10 an optical system is provided, including a longitudinally arcuate etched glass or plastic screen 20 mounted on a supporting frame 21. This frame comprises two vertically spaced plates 21a and 21b provided with correspondingly curved front edges 22a and 22b, notched at 23 and supported in spaced relation by end blocks 24. By projecting means to be subsequently described, an optical image of a plurality of characters is formed on screen 20.

Spaced rearwardly from the screen 20 are two transversely spaced vertical brackets 30, 31, having therebetween two transverse mirrors 32 and 33. As indicated by the dashed light beam line, mirror 32 is in position to receive the optical image presented on screen 20. Mirror 32 is mounted on a shaft 34 pivotable between two positions: one, shown in dotted lines, where the light incident on the mirror from the screen is reflected to a sighting aperture 35' formed in front panel 15, as indicated by the dot-dash light beam line; and the other, shown in solid lines, where said incident light is reflected to the mirror 33, as indicated by the dashed light beam line. Mirror 33 is fixedly mounted on brackets 30, 31. Shaft 34 is provided with a handle 35 to facilitate the aforementioned pivotal movement thereof and of the mirror 32 by the operator. Shaft 34 may be further provided with suitable detent means, not shown, to provide accurate pivotal location of the shaft and mirror 32 in its two operative positions above-mentioned.

When mirror 34 is in the solid line position and reflecting the image on screen 20 to mirror 33, this image is further reflected or transmitted to mirror 36, thence to mirror 37, through objective lens 38, to mirror 39, and thence to transverse slot 40 in the top wall 12 of the housing.

Mirrors 36 and 37, like mirrors 32 and 33 extend transversely of the housing 10, and they are fixedly mounted on transversely spaced vertical brackets 41, 42. Extending between and affixed to brackets 41, 42 are transverse braces 43 which are appropriately slotted to receive and be guided upon rails 44, 45. The brackets 41, 42 and braces 43 thus provide a carriage for mirrors 36, 37, whereby they may be moved as a unit longitudinally of the machine, closer to or farther from the mirror 33 and lens 38.

Objective lens 38 is also mounted for adjustment longitudinally of the housing 10. To this end, bracket 50 depending from the top wall of the housing is provided with a horizontal shelf 51 designed with a guide-way to receive and guide platform 52 along the length thereof. Cord 56 has its ends affixed to each end of

the platform 52, and by means of suitable guide and drive pulleys 53, 54, 55, the cord 56 moves the platform along the guideway in shelf 51. Objective lens 38 is carried by platform 52 for movement therewith. The axle 56 of pulley 55, for example, may extend to the exterior of the housing and carry a handle for effecting selective forward and rearward movement of the platform 52 and objective lens 38.

Having described the optical system contained within housing 10, it is desired to consider next the means whereby an image is formed on screen 20. The bottom wall 11 of housing 10 extends beyond the front panel 15, and provides there a projecting shelf 60. A plurality of font carriers 61 are positioned upon the upper surface of shelf 60. At the inner end, each font carrier is provided with a boss 62 which depends below the shelf 60 through arcuate slot 63 and extends below the under side of bottom wall 11. An extension rod 64 is affixed to the bottom of each boss and is pivotally connected at its remote end to a pivot center pin 65 which is the center of radius of arcuate slot 63. Thus, each font carrier is tied to the pivot center pin 65 so that its movement over the surface of shelf 60 is confined to an arcuate path about said pivot center. Since the various extension rods 64 for the several font carriers will overlap when tied to a single center, it is preferable that the depending bosses 62 of successive font carriers be made to extend a little further downwardly to accommodate said overlap of the extension rods. To further facilitate the arcuate movement of the font carriers on the shelf 60 over a defined arcuate path, the bosses 62 are designed with close tolerance to the width of arcuate slot 63, and the forward ends of font carriers 61 overhang the forward arcuate end 66 of shelf 60, and rabbeted at 67 to engage about edge 66 with close tolerances. The curvatures of edge 66, slot 63, and screen 20 all have a common center at pin 65.

The structural details of the font carriers are best shown in FIGS. 3, 4, and 5. Each font carrier comprises a basic body member 70 defining the length and width of the carrier, having upstanding ridges 71 along the length thereof at each longitudinal edge. Over each ridge 71 is an inwardly overhanging strip 72 extending longitudinally for a portion of the length of carrier, defining with said ridges and basic body member a T-shaped guide channel 73 defining a guideway for slidingly holding and guiding font 74. The fonts 74 are basically opaque strips having various characters inscribed thereon, such as numerals and alphabetic letters. These characters are inscribed on the fonts in any suitable manner as to render the characters transparent to light. In order to provide for easy movement of the fonts in guideways 73, a handle 75 is provided for each assembled font and carried with a T-shaped lug 76 designed to fit with the associated font in guideway 73. The handle 75 has two depending pins 77 which engage in appropriate holes in an end of the font 74, for convenience in exchanging fonts when desired.

A lens housing 80 is secured on the top of the font carrier at an appropriate place thereon over a hole 81 in the bottom of the carrier. Housing 80 has a vertical hole 82 tapped therein positioned to register over hole 81. A horizontal threaded hole 83 is also tapped in housing 80 which intersects with hole 82, and at the intersection an angular mirror 84 is provided to reflect light transmitted up hole 82 out along hole 83. A suitable lens 85 is mounted in threaded barrel 86. Barrel 86 is adjustably threaded into hole 83 to obtain a correct focus for lens 85, and a lock nut 87 may be provided on barrel 86 to fix the barrel in a desired adjusted position.

When a light beam is directed upwardly through hole 81, lens 85 will transmit an image of whatever character on font 74 is registered over hole 81. To facilitate the selection of such character, one strip 72 may have the font characters inscribed thereon, while the other strip 72 may have detent stops drilled therein cooperating with a spring pressed ball detent in handle 75, so that by sliding

of handle 75 to the desired character marking on the font carrier, the corresponding character inscribed on font 74 is located over hole 81.

With reference to FIGS. 1 and 2, it will be seen that shelf 60 has a second arcuate slot 88 over which the hole 81 in each font carrier registers. A light source 90 is supported under housing 10 and directed toward mirror 91 carried by bracket 92 under shelf 60. Mirror 91 extends the length of slot 88, and is positioned to reflect light from source 90 up through holes 88 into lens housings 80, when the font carriers are in operative position on shelf 60. The light thus received in housings 80 is reflected by mirrors 84 through lenses 85, whence the light travels through slot 15' into housing 10 and onto screen 20.

From the foregoing structural description, the operation of the present machine will be apparent. A word or other desired symbol is designated by setting successive fonts 74 with the selected sequence of letters or characters positioned over openings 81. This may be done by sliding handle 75 into registry with the desired character inscribed on strip 72. This action places the selected font characters in registry with openings 81. With the sequence of fonts set in their respective font carriers to register the desired sequence of characters with the apertures 81 in the font carriers, the light from source 90 impinging upon mirror 91 is reflected upwardly through apertures 81, thus projecting an image of the selected font characters onto mirrors 84, from whence the images are reflected through lenses 85 and focused on the screen 20. By means of handle 35, mirror 32 is placed in the dotted line position, to reflect the image now focused on screen 20 toward sight aperture 35', whereby the operator can observe the composition of the word or other desired symbol selected from the fonts. The vertical alignment of the several selected characters can now be set with precision in accordance with the operator's observation, by longitudinally shifting the fonts in their carriers. Likewise, by shifting the font carriers individually or in groups transversely across the face of shelf 60, the spacings between the selected characters can be adjusted with precision to the visual satisfaction of the operator. Thus, the entire composition of the symbol or message line is determined to the visual satisfaction of the operator. Once satisfied with the composition of the line, by means of handle 35 mirror 32 is shifted to the solid line position, whereby the image on screen 20, as thus composed, is reflected by means of mirrors 33, 36, and 37 to lens 38, from whence it is projected onto mirror 39 and reflected up through slot 40. As will be subsequently described, a photographic plate or the like may be mounted over aperture 40 to receive the message image.

As previously mentioned, plate 16 is spaced upwardly from housing bottom wall 11 providing an aperture 18 in the housing. As is now apparent, the purpose of this aperture is to accommodate and receive the inner ends of fonts 74 when they are adjusted to extend beyond the inner ends of the font carriers.

Although not shown, it is preferred in practice to provide an auxiliary cover or housing adjacent the front panel 15 and covering the area of slots 63 and 88, for the purposes of appearance and shielding the eyes of an operator from the light transmitted up through the slots 63 and 88.

In the preferred embodiment of the present machine, the image produced on screen 20 is many times larger than that projected on the film through aperture 40. By this expedient, any minor errors in composition judgment of the operator are grossly reduced in magnitude. However, the size of the image projected through aperture 40 may be varied. For this purpose, the bracket assembly 41, 42, 43, 43 and mirrors 36, 37 carried thereby is shiftable longitudinally of the machine on tracks 44, 45. In order to properly focus the image projected through aperture 40 for various positions of mirrors 36,

37, the lens 38 is likewise shiftable longitudinally of the machine, as is effected by movement of cord 56 over pulleys 53, 54, 55. Since the position of lens 38 is a definite function of the position of mirrors 36, 37, it is apparent that the movement of the two units may be mechanically linked together. However, since such linkage forms no part of the present invention, and effecting the same would be apparent to one skilled in the art, for the purpose of clarity it is omitted from the drawing. Alternatively, the carriage comprising brackets 41, 42, 43, 43 may be designed to be independently shiftable along tracks 44, 45. If desired, this may be conveniently accomplished by making top wall 12 of housing 10 removable or hinged to permit access to this carriage, the details of which have likewise been omitted from the drawings for clarity.

It has been found that the quantity of light necessary for visually composing the image on screen 20 (mirror 32 in dotted line position) is normally substantially less than that necessary for photographically recording the image through aperture 40. Accordingly, a switch 95 is carried by the housing 10, and operated by arm 96 extending from shaft 34, to control the power applied to light source 90. When arm 96 and mirror 32 are in the dotted line position, less power is applied to light source 90, while when arm 96 and mirror 32 are in the solid line position, more power is applied. Of course, a manual master switch would conventionally be provided to render the light source 90 inoperative when the machine is not in use.

With particular reference to FIGS. 1, 6, and 7, the mounting for a photographic plate over slot 40 for recording the image on screen 20 will be described. To either side of slot 40 in top wall 12 of housing 10 there is provided a grooved trackway 101 and 102 for receiving the depending pins 111, 112, 113, and 114 of a first film plate carrier frame 105. By this means, this carrier frame is adapted to be slidably guided transversely of the housing 10. By means of angle members 106 and 108, first frame member 105 is adapted to slidably receive and guide second film plate carrier frame member 107 for sliding adjustment therealong longitudinally of housing 10. It is thus readily apparent that a film plate or the like when mounted on frame member 107 can be adjusted transversely and longitudinally over the slot 40. Accordingly, successive lines of symbols can be projected onto successive lines of symbols can be projected onto successive areas of the film plate as desired. To facilitate accurate positioning of the film plate and its carriers over the slot 40 in successive positions, suitable calibrations 103 and 109 may be provided for cooperation with appropriate index markers 104 and 110.

Having thus described one specific exemplary embodiment of the present invention to facilitate an understanding thereof, it is not intended that the present invention be considered as limited thereto, since numerous variations and modifications within the scope and purview of the invention will be apparent to those skilled in the art. For example, although it is preferred that the several font carriers be all tied to a common pivot center, such not essential, for with bosses 62 riding in slot 63 and rabbet 67 engaging edge 66, the tie rods or extensions 64 may if desired be eliminated. Further, the basic concept of the present invention could be effected with the font carriers lying free on shelf 60, relying wholly on manual and visual adjustment thereof. And in this connection, it is certainly not intended, although preferred, to be limited to arcuate adjustment of carriers 61 and an arcuate screen at 20, for other configurations could be employed if desired. It is also not intended to exclude from the scope of the present invention the possibility of tilting the font carriers about their longitudinal axes, to obtain various graphic effects in the optical image. And in this connection, it is contemplated that various curved mirrors could be used at

75

32, for example, to obtain all sorts of variations in the appearance of the font characters when recorded. Further, it is apparent that numerous variations could be employed in the optical system as expediencies may dictate. Accordingly, it is intended that the scope of the present invention shall be determined from the spirit and scope of the appended claims.

What is claimed is:

1. A composing and recording machine, comprising a housing, said housing including a support means, a plurality of optical projectors, means defining a common focal area in said housing for said projectors, means mounting said projectors on said support means with their optical axes converging on the opposite side of said focal area from said projectors, said mounting means including means providing for individual adjustable movement of each of said projectors relative to the others to shift the point of intersection of the optical axis of such projector with said common focal area, each said projector including means for adjustably holding a character font in position therein for projecting an image of a selected character from such font to said common focal area, simultaneously projected images thereby being adjustable and composable by the relative positioning of said projectors, and means for effecting an optical recording of said images.
2. A composing and recording machine as set forth in claim 1, and further comprising means for resolving said projected images into observable form to permit said adjustment and composition of said projected images to the visual satisfaction of an operator.
3. A composing and recording machine as set forth in claim 2, and further comprising means for selectively presenting said projected images to the visual observation of an operator and to said recording means.
4. A machine as set forth in claim 1, and further including in said housing means providing two alternate optical paths for said projected images, one of said optical paths directing said projected images to a visual observation station, and the other of said optical paths directing said projected images to said optical recording means.
5. A composing and recording machine, comprising a housing, said housing including a support means, a plurality of optical projectors, means defining a common focal area in said housing for said projectors, means mounting said projectors on said support means with their optical axes converging on the opposite side of said focal area from said projectors, said mounting means including means providing for individual adjustable movement of each of said projectors relative to the others to shift the point of intersection of the optical axis of such projector with said common focal area, each said projector including means for adjustably holding a character font in position therein for projecting an image of a selected character from such font to said common focal area, simultaneously projected images thereby being adjustable and composable by the relative positioning of said projectors, an optical image recording station, and means in said housing providing alternate optical transmission paths for said projected images, one such path to a visual observation station, and the other such path to said recording station.
6. A machine as set forth in claim 5, and further including means, in at least one of said transmission paths, for resolving said projected images into observable form to enable visual adjustment and composing of the projected images.
7. A composing and recording machine, comprising a housing, said housing including a support means, a plurality of optical projectors, means defining a common focal area in said housing for said projectors, means mounting said projectors on said support means for individual adjustment relative to each other of the lines of their optical axes to said common focal area, each said

projector including means for adjustably holding a character font in position therein for projecting an image of a selected character from such font to said common focal area, simultaneously projected images thereby being adjustable and composable by the relative positioning of said projectors, an optical image recording station, and means in said housing providing alternate optical transmission paths for said projected images, one such path to a visual observation station, and the other such path to said recording station.

8. A machine as set forth in claim 7, and further including means in at least one of said transmission paths for resolving said projected images into observable form to enable visual adjustment and composing of the projected images.

9. A composing and recording machine, comprising a housing, said housing including a support means, a plurality of optical projectors, means defining a common focal area in said housing for said projectors, means mounting said projectors on said support means for individual and separate guided bodily shiftable movement relative to each other on a line approximately equidistant along the optical axis of each said projector from said common focal area, each said projector including means for adjustably holding a character font in position therein for projecting an image of a selected character from such font to said common focal area, simultaneously projected images thereby being adjustable and composable by the relative positioning of said projectors, and means for effecting an optical recording of said images.

10. A composing and recording machine, comprising a housing, said housing including a support means, a plurality of optical projectors, a common focal area in said housing for said projectors, means mounting said projectors on said support means for individual guided bodily shiftable movement relative to each other on a line approximately equidistant along the optical axis of each said

projector from said common focal area, each said projector including means for adjustably holding a character font in position therein for projecting an image of a selected character from such font to said common focal area, simultaneously projected images thereby being adjustable and composable by the relative positioning of said projectors, an optical image recording station, and means in said housing providing alternate optical transmission paths for said projected images, one such path to a visual observation station, and the other such path to said recording station.

11. A machine as set forth in claim 10, and further including means in at least one of said transmission paths for resolving said projected images into observable form to enable visual adjustment and composing of the projected images.

12. A machine as set forth in claim 11, wherein said mounting means includes a track means for guiding said projectors in an arcuate path of movement, said resolving means comprises an arcuate screen positioned in said focal area, and said optical transmission means including a shiftable mirror positioned to reflect the image resolved on said screen in said alternate paths.
